UNITED STATES PATENT OFFICE.

OTIS B. KENT, OF WASHINGTON, DISTRICT OF COLUMBIA, AND ROBERT L. MILLER, OF SPOKANE, WASHINGTON; SAID MILLER ASSIGNOR TO OTIS AUTOMATIC TRAIN CONTROL, INC., OF SPOKANE, WASHINGTON, A CORPORATION OF WASHINGTON.

RAMP DEVICE FOR AUTOMATIC TRAIN-CONTROL SYSTEMS.

Application filed January 13, 1922. Serial No. 529,011.

To all whom it may concern:

Be it known that we, OTIS B. KENT and ROBERT L. MILLER, citizens of the United States, and residents of the city of Washington, District of Columbia, and Spokane, in the county of Spokane and State of Washington, respectively, have invented certain new and useful Improvements in Ramp Devices for Automatic Train-Control Systems, of which the following is a specification.

Our invention relates to improvements in track mechanisms for automatic train control systems, and it consists more particularly of a ramp device which is capable of movement into and out of the path of travel of a shoe constituting a part of the train carried mechanisms whereby, under predetermined conditions, said shoe may be actuated to cause the train carried mechanism to act on the air brakes of the train thereby to control the travel of the latter.

An important purpose of our invention resides in the provision of a ramp device of the character mentioned which is of simple and comparatively inexpensive construction, possessing few parts compactly arranged and unlikely to get out of order, which is gravity-operated to a normally active shoe actuating position, and which may be electrically or otherwise operated to inactive position, being capable of quick recovery from the latter position to normal or active position.

Other purposes as well as the nature and advantages of our improvements will be apparent to those skilled in the art to which our invention appertains when the accompanying drawings are considered in the light of their related detailed description, in which connection it will be understood that changes and desirable additions may be made in and to the structure illustrated without departing from the spirit and scope of our invention as defined in the appended claims.

In the drawings wherein like characters of reference denote corresponding parts in the different views:—

Fig. 1 is a longitudinal section through a ramp device embodying the novel features of our invention, the shoe actuating member being shown in normal or active position;

Fig. 2, a view similar to Fig. 1 showing

hinged ramp rails associated with our device to be actuated thereby; and

Fig. 3, a view similar to Fig. 2 showing a modification of our invention.

Referring now to the drawings in detail, particularly to Figures 1 and 2, 10 designates an elongated hollow casing which serves as a housing and support for the movable elements of our device and which is adapted to be secured in any suitable manner at a desired location along the tracks of a railroad to dispose said movable elements in position to actuate a train carried shoe 11 connected in any preferred manner to suitable mechanism whereby actuation of said shoe will, under predetermined conditions, act through said mechanism to control the travel of the train. The specific type of mechanism to be actuated by our improved ramp device constitutes no part of our present invention and we have therefore illustrated only the shoe element of one form of such mechanism to show the relation between our device and that part of a train carried mechanism which it is designed to actuate.

With more particular reference to the drawings, it will be observed that the casing 10 is provided with a slot 12 opening through its upper surface and that operating in said slot is a member 13. This member consists of a lever which is intermediately pivoted as at 14 for swinging movement in a vertical plane, and one end of the same is weighted as at 15 thereby to cause its other end portion 16 to project through the slot 12 and be disposed normally in shoe actuating position. The upper edge of the end portion 16 is of rounded cam shape whereby the shoe 11 will ride upward thereon as it moves over the mechanism in either direction.

Flexibly connected in any suitable manner with the end portion 16 of the member 13 is the core 17 of a solenoid winding 18, which latter when energized effects a pull on the core 17 and thereby depresses the end 16 of member 13 out of the path of travel of the shoe 11. The winding 18 may be connected with a block signal system in any preferred manner whereby it will be energized upon predetermined movement of the semaphore arms or signaling devices of the system, or the same may be energized at

proper times in any other manner, and when deenergized will permit the member 13 immediately to return to or recover its normal position under the influence of the weight 15, as is apparent.

The arrangement described in the foregoing constitutes a complete ramp device for operating the shoe of a train carried automatic brake control mechanism, but in 10 some instances it may be desired to provide ramp rails instead of the member 13 for direct engagement with the shoe to effect its operation, in which event, as shown in Fig. 2, we have provided an arrangement embodying ramp rails which may be moved to active and inactive positions by the member 13. This arrangement consists of a ramp rail 19 hinged at one end to the casing 10 and at its other end to a second ramp 20 rail 20, the free end of which latter rests 25 slidably on the casing. The pivotal or hinged connection between the rails overlies the cam end of member 13 so that as said member is raised or depressed corresponding movement is imparted to said rails.

In Fig. 3 a slightly different structural arrangement is illustrated for accomplishing the same purpose in substantially the same manner as the structure illustrated in 30 Figures 1 and 2. This modified arrangement includes a hollow casing 10^a having pivoted therein a cam member 13^a of peculiar shape for raising and lowering a pair of ramp rails 19^a and 20^a, both of which 35 are pivoted at their outer ends to the casing and have their inner ends disposed relatively in juxtaposition in overlying relation to the cam 13^a. The cam member 13^a is of substantially horseshoe shape and its 40 pivot is near the free end of one of its arms and its other arm is weighted as at 15^a whereby a part of its intermediate portion which is formed into cam shape similarly to the member 15 is normally disposed above 45 the casing and holds the rails 19^a and 20^a normally elevated.

The means for depressing the member 13^a into the casing to allow the ramp rails to drop down from their elevated shoe actuating position consists of a rod 21 pivoted at one end as at 22 to the casing and extending past the member 13^a toward a solenoid winding 18^a. On or near the free end of this rod is provided a core 17^a for 50 the winding 18^a and a pin 23 on the member 13^a is disposed in a slot 24 in the rod whereby upon energization of the winding 18^a a pull is exerted on the core to move

the free end of the rod downward and thereby transmit such movement to the member 13^a by reason of said pin and slot connection. The member 13^a is operable to actuate a shoe either with or without the ramp rails 19^a and 20^a the same as member 13.

From the foregoing description taken in connection with the accompanying drawings it is believed that the construction and operation of our device will be clearly understood, and while we have herein illustrated and described one specific embodiment of our invention the same is not limited to the details shown, except to such limitations as may be contained in the appended claims.

We claim:—

1. A ramp device for automatic train control apparatus including a pair of upwardly projectible ramp rails pivotally connected together, a weight operated member normally exerting an upward force at the point of pivotal connection of said rails to maintain the latter normally projected, and electro-magnetic means to retract said member thereby to permit retraction of said ramp rails under the influence of gravity.

2. A ramp device for automatic train control mechanisms comprising a casing, a pair of pivoted, projectible and retractible ramp rails carried by said casing, an intermediate pivoted member one end of which is of cam shape and the other end of which is weighted to normally project its cam shaped end into direct contact with said ramp rails to normally project the latter, and means to retract the cam shaped end of said member thereby to permit depression of said ramp rails under the influence of gravity.

3. A ramp device for automatic train control apparatus comprising a casing, a member within said casing pivoted intermediate and having one end weighted whereby its other end is maintained normally elevated, a pair of projectible, gravity depreessible ramp rails carried by said casing, said ramp rails being pivotally connected together, an operative connection between the normally elevated end of said member and said ramp rails whereby the latter are maintained normally projected, and electro-magnetic means for retracting the normally elevated end of said member whereby said ramp rails may be depressed by gravity.

In testimony whereof we hereunto affix our signatures.

OTIS B. KENT.
ROBERT L. MILLER.
